UNITED STATES PATENT OFFICE.

CHARLES L. PORTER, OF CHICAGO, ILLINOIS.

COMBINATION-TOOL.

SPECIFICATION forming part of Letters Patent No. 783,800, dated February 28, 1905.

Application filed September 19, 1902. Serial No. 124,078.

To all whom it may concern:

Be it known that I, CHARLES L. PORTER, a citizen of the United States, residing at Chicago, in the county of Cook and State of Illinois, have invented certain new and useful Improvements in Combination-Tools; and I do hereby declare the following to be a full, clear, and exact description of the invention, such as will enable others skilled in the art to which it appertains to make and use the same.

This invention relates to improvements in a combination-tool the stock of which is so shaped as to form a coöperating wrench and can-opener. It is also preferably provided with several other devices which add greatly to its utility.

In the drawings, Figure 1 is a side elevation. Fig. 2 is a longitudinal section on line 2, Fig. 1, looking in the direction indicated by an arrow; and Fig. 3 is a transverse section on line 3, Fig. 1. Fig. 4 is a transverse sectional view through the lugs and can-opener blade on the line 4 4 of Fig. 1.

A represents the stock or handle, which is tapered to form a point at one end and tapered also transversely at the said end to form two cutting edges diverging from the said point, the said point and edges forming a can-opener blade C. A wrench feature is formed by companion rigid jaws D projecting at right angles from the stock and located at the base of the said can-opener blade C. These jaws D are spaced apart to engage a small nut and are adapted to serve as fulcrums for the can-opener blade. The said stock is also preferably provided with the following devices, which materially increase the range of its utility. On the end opposite the can-opener the stock is fashioned into a screw-driver B. Between the can-opener blade C and the screw-driver B is a longitudinal elongated slot-opening b. A plate 4 forms a part of the stock and is located in the slot-opening b and somewhat nearer to the can-opener end. This plate is cut away on the front side, forming a seat or backing 5 for the reception of an instrument-sharpening emery-disk 6, the periphery of which also bears against a curved shoulder 7, formed in the cut-away surface of the plate. The side walls of the slot-opening

b are curved out to form a jog 8, Fig. 1, corresponding to the periphery of the disk and provide a bearing therefor in connection with shoulder 7 and expose a certain proportion of the sharpening-surface for the convenient contact of the instrument to be sharpened in holding it at the right angle. With this object in view the inner adjacent sides of the slot-opening are very slightly curved, so as to present substantially V-shaped notches 9, in which an object like the blade of a knife may be inserted for the purpose of sharpening the same. In the operation of sharpening a knife the screw-driver end of the device is held in one hand, the opener-blade end being made to bear on a substantial support, and the knife-blade inserted in the notches 9 and drawn through as often as may be necessary.

The notches 10 are of a less depth and present sides of a more obtuse angle in comparison with notches 9. This is for the purpose of making these parts correspond to the bevel cutting edges of shears or scissors, so that the same may be properly sharpened without impairing the cutting action.

The sharpening-disk is adjustably secured in place by a bolt 11, which provides for the turning of the disk in bringing all of the sharpening-surface into use from time to time as may be necessary.

The plate 4 is provided with the contracted extension part 12, which is cut away adjacent to the end to form a shoulder 13. A corkscrew 14 has the shank end 15 thereof bent around at right angles and pivotally inserted in the end of extension part 12 in advance of shoulder 13. The walls of the slot-opening are beveled along their inner sides, as at d, so as to contract or narrow the space between for the reception of the corkscrew, the exterior surface of the coils of which will impinge on the beveled surface with a slight wedging action and loosely retain the corkscrew in its closed position, as best shown in Fig. 3. When required for use, the corkscrew may be turned outward to the position shown in Fig. 2 and at right angles with the stock, which serves as a handle therefor. When turned outward to its open position for use, the corkscrew comes to a stop on shoulder 100

13, which limits its open movement and assists in retaining the same in its right-angled position with reference to the handle part. By this arrangement a number of useful devices 5 may be added to the stock provided with a can-opener blade and a wrench coöperating therewith, which really composes my invention and greatly increases its convenience.

Having thus described my invention, what 10 I claim, and desire to secure by Letters Patent, is—

A tool consisting of a stock tapering to a point at one end and also tapering transversely

at said end, forming sharpened lateral edges, and a wrench formed by a pair of lugs, curved 15 on their outer surface, extending perpendicular to one side of the stock and in transverse alinement, said sharpened lateral edges serving as a reversible can-opener blade and the lugs as fulcrums about which the blade may 20 be rocked.

CHARLES L. PORTER.
